UNITED STATES PATENT OFFICE.

IRA L. GOODRICH, OF CUPERTINO, CALIFORNIA, ASSIGNOR OF ONE-HALF
TO ELMER E. RUPERT, OF SUNOL, CALIFORNIA.

MUSIC-LEAF TURNER.

No. 826,240.

Specification of Letters Patent.

Patented July 17, 1906.

Application filed February 18, 1906. Serial No. 301,415.

To all whom it may concern:

Be it known that I, IRA L. GOODRICH, a citizen of the United States, residing at Cupertino, in the county of Santa Clara and State of California, have invented new and useful Improvements in Music-Leaf Turners, of which the following is a specification.

My invention relates to music-leaf turners. Its object is to provide a leaf-turning device which can be attached to any musical instrument, such as a cornet or a piano, and by which the leaves are turned separately, either back or forward, by a push-key.

The invention consists of the parts and the construction and the combination of parts, as hereinafter more fully described and claimed, having reference to the accompanying drawings, in which—

Figure 1 is a perspective view of the invention applied to the music-rack of a piano. Fig. 2 is an elevation, partly in section, of same. Fig. 3 is a plan view of the segmental mutilated gear. Fig. 4 is a front view of the same.

25 A represents a bed-plate which is adapted to be secured to any suitable support. This support may be a part of a wind instrument, like a cornet, or it may be the music-rack on the piano. This bed-plate has a flange 2 at one end with a slot 3 and a pin 4 at the other end. The music-leaf-turning attachment has a base B, which has a tongue or tang part 5 to fit the slot 3 and a perforation 6 to receive the pin 4. A screw 7, carried by the bed-plate, is adapted to lock the attachment in operative position.

The music-leaf-turning arrangement comprises a segment 8, which is pivoted in the base B. This segment carries three gear-segments 9, 10, and 11. Each of these gears is adapted to engage successively a corresponding pinion 12, 13, and 14, which pinion operates respective rock-shafts 15, 16, and 17. Shaft 16 is a central one and has a gear 13 fixed directly to it. Gear 12 is mounted on a sleeve 18, which has an offset arm in which the shaft 15 is brazed or otherwise made a part thereof. Gear 14 is carried by a sleeve 19, which has an offset arm in which the shaft 17 is rigidly mounted. Sleeves 18 and 19 are concentric with shaft 15 and all turn independently. Rock-shafts 15, 16, and 17 have respective lateral arms 20, and the arms 20 and the vertical shafts are provided

with suitable spring-clips 21 to hold a loose sheet of music 22. The segment 8 is operated by any suitable means, as the pivoted stem 23, having the push-button 24. Stops 25 limit the arc of movement of the arms 20 in either direction. These stops are shown as carried by the top plate C.

When the push-button 24 is out to its farthest limit, the three arms 20 will lie side by side. Pushing it a third of the way in will operate the gear 12 to rock the shaft 15 and turn the first sheet of music. Pushing another third of the way in on the push-key will cause the gear 10 to rock the shaft 16 and turn the second sheet, &c. Pulling out on the key turns back each sheet of music separately. One important feature of this invention is that any sheet can be turned positively in either direction by reciprocating the key-stem properly.

Manifestly there may be any desired number of gear-segments and corresponding pinions, sleeves, shafts, and sheet-holding means.

Having thus described my invention, what I claim, and desire to secure by Letters Patent, is—

1. In a music-leaf turner, a suitable support, a rotatable part journaled therein and provided with a plurality of successively-arranged segments disposed in different planes, a rock-shaft provided with a pinion, a sleeve concentric with the rock-shaft and turnable independently thereof and provided with a pinion, a second sleeve concentric with the first sleeve and turnable independent thereof and provided with a pinion, said sleeve having offset arms, music-leaf-holding devices carried by said rock-shaft and said arms, said several pinions arranged in different planes and engageable successively by the said segments.

2. A music-leaf turner comprising a suitable support, a rockable part journaled therein and provided with a plurality of successively-arranged gear-segments in different planes, a plurality of pinions coaxial with each other and independently turnable and engageable with respective of said gear-segments, a shaft connected direct with one of said pinions, sleeves surrounding the shaft and connected with the other pinions, said sleeves having offset arms, shafts carried by said arms and arranged substantially paral-

lel with the first-named shaft, lateral projections on said several shafts, and leaf-holding means on said projections and shafts.

3. A music-leaf turner comprising a suitable support, a rockable part journaled therein and provided with a plurality of successively-arranged gear segments in different planes, a plurality of pinions coaxial with each other and independently turnable and each engageable with one of said gear-segments, a shaft connected direct with one of said pinions, sleeves surrounding the shaft and connected with the other pinions, said sleeves having offset arms, shafts carried by said arms and arranged substantially parallel with the first-named shaft, lateral projections on said several shafts, leaf-holding means on said projections and shafts, a push-key connected to the rockable part to rotate the same, and stop means in the path of said lateral projections to limit the rotative movement of the shafts.

4. A music-leaf turner comprising a suitable support, a unitary rockable part journaled therein and having a plurality of successively-arranged gear-segments, said segments being disposed in different planes and each being rigid with the rockable part, a rock-shaft, sleeves concentric with each other and with the rock-shaft, said sleeves and rock-shaft independently turnable, and said sleeves having offset arms, gears on the shaft and on the respective sleeves engageable successively by the gear-segments on said rockable part, leaf-holding means carried by said shaft and the arms of said sleeves, and means to limit the rotative movement of the sleeves and shaft.

5. A music-leaf turner comprising a suit-

able support, a rockable part journaled there- 40 in and having a plurality of successively-ar- ranged gear-segments, a rock-shaft, sleeves concentric with each other and with the rock- shaft, said sleeves and rock-shaft independ- 45 ently turnable, gears on the shaft and on the respective sleeves engageable successively by the gear-segments on said rockable part, said sleeves having lateral projections, shafts carried by said projections and arranged substan- 50 tially parallel with the first-named shaft, lateral arms on the several shafts, leaf-holding means on the several shaft-arms, and means to rock said rockable part.

6. A music-leaf turner comprising a suit- 55 able support, a rockable part journaled there- in and having a plurality of successively-ar- ranged gear-segments, a rock-shaft, sleeves concentric with each other and with the rock - shaft, said sleeves and rock - shaft independ- 60 ently turnable, gears on the shaft 60 and on the respective sleeves engageable successively by the gear - segments on said rockable part, said sleeves having lateral projections, shafts carried by said projec- 65 tions and arranged substantially parallel 65 with the first - named shaft, lateral arms on the several shafts, leaf - holding means on the several shaft - arms, stop means to limit the rocking movement of said arms, and a push-key connected to the rockable part to 70 rotate the same.

In testimony whereof I have hereunto set my hand in presence of two subscribing wit- nesses.

IRA L. GOODRICH.
